UNITED STATES PATENT OFFICE

153,371

DESIGN FOR A BUTTON

Edward D. Martin, Newington, Conn., assignor to Colt's Manufacturing Company, Hartford,
Conn., a corporation of Connecticut

Application January 2, 1948, Serial No. 143,520

Term of patent 14 years

(Cl. D17—2)

To all whom it may concern:

Be it known that I, Edward D. Martin, a citizen of the United States, residing at Newington, in the county of Hartford and State of Connecticut, have invented a new, original, and ornamental Design for a Button, of which the following is a specification, reference being had to the accompanying drawing, forming part thereof.

In the drawing:

Fig. 1 is a plan view of a button, embodying my new design.

Fig. 2 is a side view thereof.

The stippled and unstippled portions of the drawing are intended to represent different colors.

I claim:

The ornamental design for a button, as shown and described.

EDWARD D. MARTIN.
